UNITED STATES PATENT OFFICE.

JOHN L. WHITEHURST AND CHARLES H. WILD, OF BALTIMORE, MARYLAND, ASSIGNEES,
BY MESNE ASSIGNMENTS, TO JOHN T. WHITEHURST, OF BALTIMORE, MARYLAND.

LABELING-MACHINE.

1,323,940.

Specification of Letters Patent.

Patented Dec. 2, 1919.

Application filed November 20, 1915. Serial No. 62,446.

To all whom it may concern:

Be it known that we, JOHN L. WHITEHURST and CHARLES H. WILD, citizens of the United States of America, residing at Baltimore, Maryland, have invented certain improvements in Labeling-Machines, of which the following is a specification.

This invention relates principally to a novel construction of a labeling machine, whereby certain parts of the same which have to be adjusted or changed in position to admit of the application of labels to cans of different diameters, are so combined as to form an entirety which can be moved in 15 and by a single adjusting operation, as will hereinafter fully appear.

In the further description of the said invention which follows, reference is made to the accompanying drawings, forming a part 20 hereof, and in which:

Figure 1 is an exterior side elevation of the improved machine, or of such parts thereof, as are involved in the present invention; and Fig. 2 a plan or top view of 25 the same.

Fig. 3 is an enlarged longitudinal section of certain parts of the machine.

Fig. 4 is an enlarged exterior side view of the group of elements of the machine, 30 which are collectively moved in adjusting the machine, together with certain other elements, which coöperate with them; and Fig. 5 a top view of Fig. 4 except that some parts shown in Fig. 4 are omitted or shown only 35 in dotted lines.

Fig. 6 is a view of certain parts shown in Fig. 5 looking in the direction indicated by the arrow in that figure.

Figs. 7 and 11, inclusive are detailed 40 views of parts of the machine, and herein-after described.

Referring now to the drawings, 1, 1 are spaced parallel straight bars which form the frame of the machine, and 2 represents a 45 part of the stand which supports the frame, and shown only in Fig. 1.

3 and 4 are pulleys which are tight on the shafts 5 and 6, situated respectively at the entrance, and the delivery end of the 50 machine as is usual in machines of this class.

The pulleys 3 and 4 carry the conveyer belts one of which is indicated by a dotted line in Fig. 1 and marked 7. A can shown 55 in dotted lines in Fig. 1 is denoted by a.

9, 9 are guide rails which extend the entire length of the machine between which the cans are rolled by the conveyer belts. These rails are supported at the forward end of the machine by brackets 10 which 60 are fastened to the bars 1, and at the rear end, by the standards 12 which are also secured to the bars 1, as best shown in Figs. 1 and 11. The immediate means of connecting the guide rails to the brackets and standards consists of rods 13 one of which is shown in Fig. 11.

The guide bar 9, at one side of the machine is fixed as is usual, while at the other side it is adjustable laterally of the machine to provide for cans differing in length; and for this purpose the rod 13 projects loosely through the standard 12 as shown in Fig. 11, and is provided with a thumb nut 16, and between the standard 75 and the bar 9 is a coiled spring 19 which yieldingly holds the bar at any desired distance from the standard.

Should it be necessary at any time to temporarily withdraw the movable guide 80 bar from its normal position which is in near contact with the head of a can rolling along the machine, thumb levers 20, one only of which is shown in Fig. 11, are placed between the nuts 16 and the supports, 85 which upon being pressed, overcome the tension of the springs 19, and cause the bar to be drawn outward, as will be readily understood.

As it is necessary to vertically adjust the 90 lower lay of the conveyer belts, to suit the diameter of the cans to be labeled, the shaft 5 is journaled in stands 21 whose lower ends are turned to fit loosely in the brackets 10, and when adjusted, they are held by pins b. 95

To admit of the vertical adjustment of the conveyer belts at the delivery end of the machine, they are made to pass under tension pulleys 23 whose shafts are journaled in bearings 24 at the end of the inclined bars 25 which are adapted to be slid in bosses formed on the standards 12. 100

27, 27 are straight flat bars supported at one end by the stands 21 and at the other end by sliding straps 26 connected, to, or 105 forming parts of the bearings 24, and have in consequence a vertical adjustment in common with those parts.

29, 29 are hangers depending from and attached in any suitable manner to the bars 110

27, carrying the spring-held rollers 30 which rest upon the lower lay of the conveyer belts 7; and 31, 31 are similar hangers except that they are not fastened to the bars 5 27, but adapted to slide longitudinally thereof for a purpose hereinafter described. The hangers 29^a are united to the straps 29 forming parts of the bearings 24, by links 22, see Figs. 1 and 2.

10 33 is a pot situated near the entrance end of the machine to hold heat-liquefied cement which is applied to the can bodies in the form of dabs of cement as is common in machines of this class, by means of rollers 15 which are not shown. The shaft carrying the rollers is however illustrated in Figs. 1 and 2 and denoted by 34, and it is rotated from the driving shaft 5 by the pulleys 35 and 36, and the belt 37 which is indicated 20 by a dotted line in Fig. 1.

39, 39 are standards supported by and adapted to have a longitudinal sliding movement on the bars 1; and their ends are slotted as shown in Fig. 1, to receive the 25 pins *c* which extend from the movable hangers 31.

40 is a yoke situated under and extending transversely of the bars 1, having horizontally projecting arms 42 which are bolted to 30 the standards 39.

The yoke 40 is supported by the bars 1 by means of plates *d* which project over the said bars and are held in place by screws *e*, as best shown in Figs. 4, 5 and 6.

35 43 is a hand-lever fulcrumed at *f* to the underside of one of the bars 1, and connected by a link 45 to the underside of the yoke 40, whereby the yoke and certain parts hereinafter described, can be moved backward or 40 forward of the machine in the adjusting operation.

Figs. 7, 8 and 9 are respectively a top, a side and an edge view of a bridge piece 46 the ends *g* of which are bolted to projections *h* at the base of the stands 39. The 45 holes for the bolts are denoted by *i* in Figs. 5 and 7.

The bridge-piece 46 is provided with label-curling wire 47 from under which the 50 rear end of the label is drawn at the conclusion of the labeling operation. This wire is an old device for the purpose and in itself forms no part of the present invention.

49 is an arched plate one end of which is 55 bolted at *j* to the bridge-piece, and at its other end fastened to a plate 50 in which is a pocket containing the rubber sponge block, or compression pad 52 upon which the can after being labeled is pressed by the conveyer belts. The use of sponge rubber for the purpose is old.

53 is the vertically moving table shown only in Fig. 2, upon which the labels are placed, and 55 is the fixed stop or guide 60 for the forward end of the stack of labels.

The other stop 57 depends from the movable bridge 46, and of course is adjustable with respect to the fixed stop 55. 60 is a removable paste pot hinged to a bracket 61 which is carried by a stud 62 projecting from the 70 standard 39 as shown in Figs. 2 and 5.

Heretofore, that is to say, before our present invention, the pasting belt has been pressed down and into contact with the upper label of the stack to apply paste thereto, 75 directly by the cans in rolling over it; but in the present invention we employ hinged fingers 65 which rest upon the pasting belt 77, and are in the path of the cans, as shown in Fig. 3, and the cans in their forward movement press them down upon the pasting belt which is thereby brought into contact with the label and applies paste thereto.

Referring now particularly to Figs. 2 and 10, which show certain parts of the machine 85 relating to the pasting appliances:

66 is a pulley splined on the rotary shaft 67 one end of which is journaled in the arm 69 which is practically a part of the adjacent standard 39, and at the other end connected by the gears 70 and 71 to the shaft 90 72 supported by the bracket 73.

By reference to Fig. 2 it will be seen that the arm 69 has a hook 69^a the end of which rests in a groove formed in the hub of the 95 pulley 66, and in the movement of the arm longitudinally of the shaft 67 the pulley is carried with it.

To the gear 71 is secured a pulley 74 which by means of a belt shown in broken 100 lines in Fig. 2, receives its rotation from the pulley 75 on the shaft 6.

By reference to Fig. 10 it will be seen that the pasting belt 77 passes around the paste-applying rollers 63 and 64 situated in the 105 paste pot 60, and the sliding pulley 66 on the shaft 67.

Referring again to Figs. 2 and 10, it will be seen that in the paste pot 60, there is secured a stand 61^a which carries the flanged 110 rollers 63 and 64 before referred to, and in addition, the flanged roller 63^a which is elevated above the roller 64 and the edge of the paste pot; and that the roller 63 is provided with scrapers 63^b which prevent a superabundance of paste being applied to the belt 77 in its movement toward and over the upper label of the stack of labels.

Among the advantages of the construction described, is that the paste pot can be removed from the machine without interfering with the appliances whereby paste is applied to the belt.

From the foregoing description it will be understood that the yoke 40 carrying the 125 bridge 46 with its arched plate 49 and the sponge block 52, the standard 39 which carries the paste pot 60, and the pulley 66, form an entirety which is susceptible of adjustment longitudinally of the machine, 130

thereby adapting the machine for labeling cans of various diameters requiring labels of different lengths, by means of the hand-lever 43, in a single operation of the same, 5 thus obviating the necessity of separate adjustment of the parts, which separate adjustment is not only troublesome, but requires expert knowledge rarely met with in operators of labeling machines, and that 10 the adjusting operation after a stack of labels of the required length have been placed on the table 53 with its forward end closely in contact with the permanent stop 55, is to bring the movable stop 57 up 15 to the stack by means of the hand-lever 43.

We claim as our invention:

1. In a labeling machine, the combination with the bed thereof, of practically fixed 20 devices to apply an adhesive to cans and a label stop all situated at the entrance end of the machine, a paste pot with its pasting belt, a second label stop, a label curling rod, and a compression pad, the said elements being united so as to constitute an entirety, 25 and means whereby the said entirety can be shifted longitudinally of the bed, substantially as specified.

2. In a labeling machine, a pair of standards movable longitudinally of the frame 30 carrying a paste pot with its paste-applying belt, a bridge having a pendent label stop, a label curling rod, and a compression pad, combined with an actuating yoke and a hand lever whereby a joint movement of the said 35 parts can be effected, substantially as specified.

3. In a labeling machine, endless conveyer belts for the cans horizontally placed vertically adjustable elevated bars carrying tension rollers for the belts, combined with inclined bars with pulleys at their end which support the ends of the horizontal bars, whereby in the sliding of the inclined bars the vertical height of the horizontal bars is 45 controlled.

4. In a labeling machine including means for applying an adhesive to the cans, and a label stop, all situated at the entrance end of the machine, the combination of longitudi-

nally movable means constituting a unitary 50 paste applying device, a lever fulcrumed in a fixed part of the machine, and a link connection between said lever and a member of said paste applying device, whereby said paste applying device as an entirety, may be 55 moved longitudinally of the machine, substantially as specified.

5. In a labeling machine, the combination with the bed thereof of label pasting device 60 embracing a paste pot, a pasting belt and a label compression pad, of a lever fulcrumed in a fixed part of the machine, and a link connection between said lever and a member of said paste applying device, whereby said device, as an entirety, may be moved longitudinally 65 of the machine, substantially as specified.

6. In a can labeling machine including means for applying an adhesive to the cans, and a label stop, all situated at the entrance 70 end of the machine, the combination of paste applying devices comprising a standard, a paste pot carried thereby, a yoke, a bridge borne by said yoke and having an arched plate and a sponge block, said paste applying devices constituting an entirety or a unitary structure, a lever fulcrumed to a stationary part of the machine, and a link connecting said lever to an element of said movable paste applying entirety or unitary 75 structure, whereby longitudinal movement of the latter relatively to the machine may be effected, substantially as specified.

7. In a labeling machine, label pasting devices comprising a paste pot, rollers within 80 the same, pulleys, and a pasting belt passing over said rollers and pulleys, combined with a lever and link connection between a fixed part of the machine and said pasting devices 85 whereby said pasting devices as an entirety 90 may be moved longitudinally of the machine, substantially as specified.
